UNITED STATES PATENT OFFICE.

HENRY SPENCER CLERC, OF GRETNNA, LOUISIANA.

SULFUR-FEED HOPPER.

1,332,106.

Specification of Letters Patent. Patented Feb. 24, 1920.

Application filed July 29, 1919. Serial No. 313,990.

To all whom it may concern:

Be it known that I, HENRY S. CLERC, a citizen of the United States, and a resident of Gretna, in the parish of Jefferson and State of Louisiana, have invented a new and Improved Sulfur-Feed Hopper, of which the following is a full, clear, and exact description.

My invention relates to sulfur feed hoppers of the kind used in connection with furnaces for burning iron pyrites or other sulfur ores, or in connection with furnaces used in making sulfuric acid and various other chemicals by aid of catalysis.

More particularly stated, my invention comprehends a hopper and box carried thereby, so arranged that, as a whole, the device may be readily mounted upon the furnace and so arranged that the heat of the furnace melts the sulfur contained within the hopper which thereupon flows in small quantities into the furnace.

Reference is made to the accompanying drawings forming a part of this specification and in which like reference characters indicate like parts throughout all of the figures.

Figure 1 is a side view of the furnace, shown partly in elevation, and partly broken away, as equipped with my device.

Fig. 2 is a sectional view of my improved sulfur feed hopper and is taken on the line 2-2 of Fig. 3 looking in the direction indicated by the arrows.

Fig. 3 is a plan view of my device.

A furnace is shown at 4 and is provided with a combustion chamber 5 and with doors 6, 7, these parts being of the usual or any desired construction. The furnace is provided with a face plate 8 and with a front wall 9. The furnace is also provided with a niche 11 and with a lip 12 formed from the face plate 8 and extending slightly upward into the niche 11.

The sulfur feed hopper is shown at 13 and has generally the form of a hollow wedge. It is provided with a lip 14 of considerable length, this lip having a suitable form to hook over the lip 12 so that the weight of the feed hopper rests mainly upon the lip 12 and so that the hopper, as a whole, may be readily lifted away from the furnace.

The hopper 13 is provided with a top 15 connected thereto by hinges 16. The hopper is further provided with a slanting wall 15 so formed as to rest neatly against a pro-

truding portion 10 of the face plate 8, this protruding portion being so formed that the weight of the hopper tends to press the hopper tightly against it. The hopper is further provided with a hole 18 disposed near the bottom.

A trough 19 is provided with a sulfur groove 20 and with an upwardly extending flange 21. Bolts 22 extend through the flange 21 and hold the trough 19 rigidly in position upon the hopper. The trough is so positioned that the sulfur groove 20 is practically in registry with the hole 18.

The furnace wall 9 is provided with an opening 17 of substantially frusto-conical form; as may be understood from Fig. 1.

The operation of my device is as follows: The sulfur feed hopper, as a whole, is mounted upon the face of the furnace in the manner indicated in Fig. 1. That is to say, the device is raised into position so that the lip 14 of the hopper is caused to hook over the lip 12 of the furnace, the lip 14 and hinges 16 thus extending into the niche 11. The weight of the hopper brings the face or surface 15 of the hopper into engagement with the protruding portion 10 of the furnace which has a slant, as indicated in Fig. 1. The hopper clings tightly against the protruding portion 10 of the face plate, owing to the fact that the hopper tends to rock upon the lip 12 as a center.

The furnace may be used for burning pyrites or other sulfur ores, or for consuming various fuels with which sulfur is to be burned for any purpose, as for instance, in connection with a Glover's tower or for the manufacture of sulfurous acid and various sulfur compounds. Sulfur, usually in the form known in this art as brimstone, is placed within the body of the hopper, the lid is closed and the hopper is placed in the position as above described. The furnace being in action, the heat of the furnace melts the sulfur which trickles down and following the trough 19 is discharged within the furnace. The discharge is rather slow owing to the fact that the size of the hole 18 is limited and that the sulfur feed hopper is not exposed to a high degree of heat.

This device presents a considerable number of advantages. It does not necessitate the doors 6 or 7 being open or the furnace disturbed in any other way. The sulfur feed hopper, when in position, completely closes the opening 17 and thus while in use does

not cause the constant admission of air into the furnace. The operator can handle the sulfur feed hopper without danger of being burned from the flames within the furnace.

I do not limit myself to the precise mechanism shown as variations may be made therefrom without departing from the spirit and scope of my invention.

Having thus described my invention, what I claim as new and desire to secure by Letters Patent is as follows:

1. In a sulfur feed hopper, the combination of a hollow body member provided with a lip whereby the body member may be suspended, said body member being provided with an opening, and a trough mounted upon said body member and provided with a groove in registry with said opening.
2. A sulfur feed hopper, comprising a hollow body member provided with a discharge opening, a longitudinal trough provided with a flange, bolts extending through said flange and engaging said body member for the purpose of holding said trough in position, said trough being provided with a groove in registry with said discharge opening.
3. In a sulfur feed hopper, the combination of a hollow body member provided with an opening, a trough carried by said hollow body member and disposed adjacent to said

opening, said hollow body member being provided with a lip whereby said hollow body member may be suspended, and a cover 35 hinged upon said hollow body member.

4. In a sulfur feed hopper, the combination of a furnace provided with a face plate and with an opening, said face plate being provided with a niche, and a hollow body member provided with a portion extending into said niche and with a lip for engaging said face plate at the edge of said niche in order to suspend said hollow body member upon said face plate, said hollow body member being provided with a discharge opening, and a trough mounted upon said hollow body member at a point adjacent said discharge opening, said trough extending through said opening in the wall of said 50 furnace.

5. A sulfur feed hopper, comprising a furnace provided with an opening and with a face plate, said face plate having a projecting portion which has a slanting edge, 55 a body member connected with said face plate and provided with a portion resting upon the projecting flange, said body member being provided with an opening, and a trough mounted upon said body member and disposed against said opening, said trough extending through said opening in the furnace wall.

HENRY SPENCER CLERC.
